(57) **CLAIM**

The ornamental design for an implantable support, as shown and described.

DESCRIPTION

FIG. 1 is a perspective view of an implantable support. FIG. 2 is a front elevation view of the implantable support illustrated in FIG. 1, where a back elevation view is not provided since it is identical to and duplicative of the front elevation view.

FIG. 3 is a left side elevation view of the implantable support illustrated in FIG. 1, where a right side elevation view is not provided since it is identical to and duplicative of the left side elevation view.

FIG. 4 is a top plan view of the implantable support illustrated in FIG. 1; and,

FIG. 5 is a bottom plan view of the implantable support illustrated in FIG. 1.

In FIGS. 1 and 2 the bold dashed lines illustrate the boundary between claimed fibers of mesh and portions of mesh that form no part of the claim. The boundary forms no part of the claim. The broken lines on the implantable support are for the purpose of illustrating fibers of mesh and form no part of the claim.

1 Claim, 5 Drawing Sheets
